COMBINATION BILLFOLD, MEMORANDUM PAD, AND PURSE

Howard A. Bauman, West Bend, Wis., assignor to
Enger-Kress Company, West Bend, Wis., a corporation of Wisconsin

Application September 20, 1947, Serial No. 775,325

6 Claims. (Cl. 150—35)

1

This invention relates to a combination billfold, memorandum pad and purse.

It is a primary object of the invention to provide an exceptionally compact and useful arrangement of a billfold, coin purse and memorandum pad. In achieving this objective, it is my purpose to provide an arrangement in which the coin purse is supported in part by a flap or partition having a height somewhat less than the length of a bill, and across the upper end of which bills may be folded, the folded bills being enclosed by a flap, for the free end of which the coin purse provides an anchorage.

It is a further object of the invention to provide a billfold organization in which the bills are enclosed by an end flap and have their end portions fully exposed upon the opening of the flap, while the larger areas of the bills are still housed within the fold, thus permitting the money to be counted, or permitting a particular bill to be selected from a number of bills, without exposing the several bills to the risk of loss which is involved if all of the bills are removed for either of these purposes.

Other important objects of the invention can best be described by referring to the disclosure of the invention in connection with the accompanying drawings.

In the drawings:

Fig. 1 is a view in perspective showing the billfold closed.

Fig. 2 is a view in perspective showing the billfold open.

Fig. 3 is an enlarged detail view taken in section on the line 3—3 of Fig. 2.

Fig. 4 is a view similar to Fig. 2, but showing the several flaps open to expose the billfold compartment and the coin purse compartment.

Fig. 5 is a fragmentary detail view taken in section on the line 5—5 of Fig. 4.

Like parts are designated by the same reference characters throughout the several views.

My billfold comprises the usual panel member 7 foldable upon the vertical fold line 8. At one side of the fold line, there is stitched to the back panel member 7, an inner panel section 9 which is stitched to the back panel 7 along its top margin 10, its end margin 11, and its bottom margin 12. The inner margin 13 of panel section 9 is free to provide an opening into the interior pocket formed between the inner panel 9 and the outer panel 7. Panel 9 also provides a strap 14, behind which the tab of a memorandum pad 15 is receivable as shown in Fig. 2.

Connected with the left-hand end margin 16

2 of the back panel 7 is a partition panel 17 which is stitched to the end margin 16 of the back and is further connected by a row of stitching at 18 to the bottom margin of the back. The top edge 19 and the inner side margin 20 of the partition panel 17 are free to afford access to a billfold pocket provided between panels 17 and 7. The width of panel 17 is slightly greater than the width of the currency to be received into such pocket, while the height of the partition panel 17 is approximately three-fourths of the length of the bills. Thus, when bills 21 are placed in the pocket, they are disposed vertically rather than horizontally respecting the billfold, and their upper end portions project from the pocket and are folded over the top margin 19 of the partition panel 17, as shown in Fig. 4. The back panel 7 is formed with an upwardly extending flap 23 which may, if desired, have a pocket-forming lining ply 24 to receive tickets and the like. The flap 23 is foldable over the folded ends of the bills 21, and the free end portion 25 of such flap may be anchored behind the coin purse presently to be described.

25 The coin purse is provided by the sheet of material 26 which has its inner margin 27 connected by stitching at 28 to the otherwise free inner margin 20 of the partition ply 17. Thence the sheet 26 passes about the said margin 20 of the partition ply and across the face thereof, its bottom edge being anchored by the stitching 18 previously referred to. Near the left-hand inner end of the billfold, the sheet of material 26 is folded upon itself at 29 and 30 to form a pleat best illustrated in Figs. 4 and 5. Its end is held by the stitching 31, which also connects the partition panel 17 with the end 16 of the back panel 7.

30 Near its top, the sheet or web 26 which forms the coin purse pocket is provided with a conventional male glove fastener element 33. A separate closure flap 35 is stitched at 36 to the partition panel 17 at a point well below the free margin 25 of the flap 23 which provides a closure for the billfold. Closure flap 35 extends upwardly from stitching 36 and is folded at 37 over the top margin of the web 26 which forms the coin purse, and, extending downwardly over the face of the coin purse, is provided with a female glove fastener element at 38 releasably engaged with the male element 33.

35 As best shown in Fig. 3, there is a shallow pocket between the coin purse closure flap 35 and the partition web or panel 17 in which the free end 25 of the billfold closure flap 23 is releasably engaged for anchorage. Obviously, the

55

closure flap 23 would not itself provide such anchorage. The desired result is achieved by reason of the fact that the end portion 25 of flap 23 projects well below the tops of the seams 31 and 28 by which the coin purse-forming web 26 is held to the partition panel 17.

While the billfold compartment closure is thus dependent for anchorage upon the coin purse compartment, either compartment may be opened independently of the other. Where it is desired to take advantage of the novel billfold organization disclosed herein, without providing a coin purse, other means may be provided for the anchorage of the free end of the billfold closure flap.

As a means of holding the entire billfold in the folded position in which it is shown in Fig. 1, I prefer to provide an extension flap 40 integral with the right-hand end of the back and projecting beyond the pocket-forming panel 9, said flap being adapted to be folded over the left-hand end of the back and anchored thereto by the glove fastener means 41.

The opening of the glove fastener 41 is a prerequisite to any access to bills or coins. However, the mere opening of flap 40 gives access directly to the memorandum pad only. When the pad is in use, no money is exposed. As above noted, the billfold pocket and the coin purse pocket are individually accessible through separate flaps 23 and 35 respectively.

I claim:

1. In a billfold of leather or the like, the combination with panels interconnected along a common edge to provide a billfold compartment and a coin purse compartment having openings at different distances from said common edge, of a flap closure for the coin purse compartment having a fixed marginal anchorage to the billfold along a line within the coin purse compartment whereby to provide a shallow pocket between the billfold compartment and said flap, and a closure flap for the billfold compartment having a free end portion detachably engaged in said pocket.

2. In a billfold of leather or the like, the combination with a back panel folded centrally upon itself, of a bill-retaining partition connected to one end of said back panel and extending therefrom toward the fold, said partition being connected to said panel at its bottom and having a free top and one free side edge through which currency may be introduced into the space between said partition and said panel to lie parallel to said fold, the height of the partition being less than the length of the currency, whereby the currency is foldable over said partition, a flap connected with the panel and foldable over the partition and over the end portions of currency so folded, and an anchorage on the front of the partition with which a free end portion of said flap is detachably engaged, said anchorage comprising a flap for another compartment secured to said partition and having an intermediate fold, behind which said first mentioned flap is receivable.

3. The device of claim 2 in which such anchorage flap has beneath it a coin purse marginally connected with the partition and forming a pocket with the partition into which the free end portion of said flap is inserted.

4. In a billfold, the combination with a back

panel, of a partition panel cooperating with the back panel to provide a currency-receiving pocket, the partition panel having one side and a bottom margin connected to the back panel, the other side and the top margin of the partition panel being free to receive currency, the height of the partition panel being less than the length of the currency but more than half of the length thereof, a flap connected with the back panel at its top edge and folded over the free top margin of the partition panel, and means for anchoring the free end of said flap to the face of the partition panel at a point below the end of currency folded over the partition panel beneath said flap, said anchorage means comprising a coin purse secured to the partition panel in a position to lap the portion of the free end of the folded flap aforesaid.

5. The combination set forth in claim 4 in which said coin purse comprises a web connected to the inner face of the partition panel adjacent the free side edge thereof and extending about such edge and across the face of the partition panel, said web being provided with means connecting it to a bottom portion of the partition panel and to that side portion of the partition panel which is connected with the back panel, said coin purse having a closure flap connected to said partition panel independently of said web along the line closer to said bottom portion of the partition panel than is the top margin of the coin purse and folded over said coin purse to provide an anchorage pocket.

6. A billfold of the character described including a back having top, side and bottom margins; a partition secured to the back along a side and bottom margin to receive paper currency therebetween; a flap comprising an extension of the back and foldable over the top margin of the partition; a compartment forming member secured to the partition and provided with a compartment flap, said compartment flap being secured to the partition marginally of the compartment flap at a line between the member and the partition whereby the compartment flap extends toward the top margin of the partition to form a pocket therebetween and is folded over the compartment member as a closure for the compartment; the first mentioned flap being positioned to be tucked into and retained by said pocket.
